UNITED STATES PATENT OFFICE

ALBERT TEISSÈRE AND JEAN TEISSÈRE, OF ST.-JULIEN, AUBE, FRANCE

APPARATUS FOR ENGRAVING PRINTING ROLLERS

Application filed November 20, 1928, Serial No. 320,722, and in France July 4, 1928.

This invention is an improvement over a part of the structure shown in our Patent No. 1,695,617, Dec. 18, 1928.

That patent relates to a process and apparatus for electromagnetically engraving printing rollers, according to which the pattern to be copied is reproduced on the printing roller by means of a tool that moves along the said roller and is operated by an electro-
10 magnet.

The present invention aims at improving the action of the tool, and particularly at avoiding defects in operation, notably those due to the inertia of the masses operated.

15 According to the invention, an improved operating tool and means for operating same are provided, comprising a pivoted bell-crank lever of light material carrying an engraving diamond or point on one arm, an armature in the form of a magnetic disc of very reduced mass actuating the other arm, and an electromagnet in the form of a pot to operate said armature.

Further features of the invention may be 25 appreciated from the following description of a preferred form of apparatus in accordance therewith illustrated in the accompanying drawing.

In the accompanying drawing:

30 Fig. 1 is a longitudinal section, and Fig. 2 is a plan view, from which some parts are omitted to assist illustration.

Referring more particularly to the drawing, a is a magnet in the form of a pot with a 35 central core a' carrying a solenoid b , the whole being accommodated in an aluminium casing c provided with a device c' for securing it on the engraving machine. In the chamber formed by a cover d of non-magnetic 40 material and the magnet a, a' , is disposed an armature e in the form of a disc, the mass of which is reduced as much as possible, the armature e being guided on one side by a shaft f of non-magnetic metal accommodated 45 in the core a' and on the other side by a shaft g passing through the cover d . A spring h , the tension of which can be adjusted by slackening a holding screw h' and sliding a bracket h'' up or down a fixed rod h''' , acting 50 on the extension of the shaft g at its

upper end, brings the disc e back to its position of rest after each interruption of the current in the solenoid b , the air imprisoned between the disc e and the cover d , as it is more and more compressed by the movement 55 of the disc, having a checking or dash-pot effect. The movement of the armature e is transmitted to the tool by means of a bell-crank lever k, l , of which the arm k carries at its upper part a finely adjustable screw m 60 provided with the engraving diamond i . In order to reduce as much as possible the bad effects of mass inertia, the lever k, l , through which passes the extension of the shaft g , is formed as a trunnion, which is held between 65 the shaft g and a spring washer n by a nut, to prevent all play while not impeding its mobility.

We claim:

1. In apparatus for electro-magnetically 70 engraving printing rollers: an engraving point and means for operating the same, comprising a pivoted bell-crank lever of light material carrying the engraving point on one arm, an armature in the form of a magnetic disc of very reduced mass actuating the other arm, and an electro-magnet in the form of a 75 pot to operate said armature, the arrangement being such that the disc armature is received in said electro-magnet. 80

2. Apparatus of the type set forth, comprising a pivoted bell-crank lever of light material, carrying an engraving point on one arm, an armature in the form of a magnetic disc of very reduced mass connected to the other arm, an electro-magnet in the form of a pot to operate said armature and a cover for the electro-magnet forming a chamber therewith in which said armature disc is enclosed, so that the compression of the imprisoned air by the disc in action may have 85 a dash-pot effect. 90

3. Apparatus of the type set forth, comprising a pivoted bell-crank lever of light material carrying an engraving point on one arm, an armature in the form of a magnetic disc of very reduced mass actuating the other arm, an electro-magnet in the form of a pot to operate said armature, a cover for the 95 electro-magnet forming a chamber therewith 100

in which said armature is enclosed, elastic means to return the armature to its position of rest after each interruption of the current in the electro-magnet and means to adjust the tension of said elastic means.

4. Apparatus of the type set forth, comprising a pivoted bell-crank lever of light material carrying an engraving point on one arm, an armature in the form of a magnetic disc of very reduced mass actuating the other arm, an electro-magnet in the form of a pot to operate said armature, a spring to return the armature to its position of rest after each interruption of the current in the electro-magnet, said spring acting on an extension forming part of the armature, a sliding bracket to adjust the tension of said spring, means to fix said sliding bracket in a required position, a trunnion forming part of said bell-crank lever and through which passes said extension of the armature, and washers for holding said trunnion between them to prevent all play while not impeding the mobility.

25 In testimony whereof we signed hereunto our names.

ALBERT TEISSÈRE.
JEAN TEISSÈRE.
